(57) CLAIM

The ornamental design for a communication device, as shown and described.

DESCRIPTION

FIG. 1 is an upper perspective view of the communication device showing my design in an assembled configuration with a headset component attached to a cradle component and with markings and attachments in broken lines; FIG. 2 is a side elevation view thereof with markings and attachments in broken lines; FIG. 3 is an opposite side elevation view with markings and attachments in broken lines; FIG. 4 is a top plan view thereof with markings and attachments in broken lines; FIG. 5 is a bottom plan view thereof with markings and attachments in broken lines; FIG. 6 is an end elevation view thereof with attachments in broken lines; FIG. 7 is an opposite end elevation view thereof with attachments in broken lines; FIG. 8 is another perspective view thereof, showing my design in a disassembled configuration with the headset component separated from the cradle component with markings and attachments in broken lines; and, FIG. 9 is still another perspective view thereof, showing my design in the disassembled configuration from another side with attachments in broken lines. The communication device is a receiver and transmitter for attachment to a motorcycle helmet. The markings and attachments in broken lines represent environment and form no part of the claimed design.
